TYPE-WRITING MACHINE.

No. 907,450.

Specification of Letters Patent. Patented Dec. 22, 1908.

Application filed September 24, 1907. Serial No. 394,835.

To all whom it may concern:

Be it known that I, EDWIN F. M. BRANSON, subject of the King of England, and resident of Leicester, England, have invented 5 certain new and useful Improvements in Type-Writing Machines, of which the following is a specification.

My invention relates to improvements in typewriting machines and more particularly 10 refers to means for effecting a quicker and more accurate centralization of short lines, headings and the like. Usually this work is done by mentally deciding upon a central point on the carriage scale as a center, say 15 number "35", then counting the number of letters and spaces in the line to be centered, halving the same, deducting the result from the "35" and so obtaining on the scale the commencing point of the line.

20 The object of the present invention is to simplify this procedure, obviate the necessity of calculation, provide a center indicator, and thus minimize the risk of deviation from the center, relieve the mind of the operator of mental strain and facilitate the production of work of the character specified.

To the above and other ends which will hereinafter appear, my invention consists of the features of construction, arrangements 30 of parts and combinations of devices to be hereinafter described and particularly pointed out in the appended claims.

In the accompanying drawings wherein like reference characters indicate corresponding parts in the different views, Figure 1 is a fragmentary vertical sectional view showing a portion of the carriage of a typewriting machine with the device of my invention applied thereto. Fig. 2 is a plan view of the 40 same. Figs. 3, 4, 5 and 6 are fragmentary detailed, sectional views of other forms of construction. Fig. 7 is a fragmentary detailed front elevation of the construction shown in Fig. 6. Fig. 8 is a diagrammatic 45 developed view of the auxiliary scale shown in Figs. 6 and 7.

The devices of my invention are shown in the present instance applied to a No. 6 Remington machine, but it should be understood 50 that they are applicable to various styles of typewriting machines. The invention is applicable to machines employing the usual or any preferred form of carriage, whether the

carriage scale be mounted on the carriage, and a coöperating pointer on a fixed portion 55 of the machine as in the Remington machine, or vice versa. I have shown in Figs. 1 and 2 a rectangular platen frame 1 of the carriage with a platen shaft 2 journaled in bearings therein, a platen 3 being mounted on the 60 platen shaft and provided with the usual finger wheels 4 at the ends thereof. The forward cross bar of the platen frame has a bearing lug 5 secured thereto and in which a roller 6 is pivoted. The roller bears upon 65 the shift rail 7 of the machine which is actuated in the usual manner to change the case position of the platen. The front cross bar of the platen frame has forwardly and downwardly extending bracket arms 8 to which a 70 carriage scale 9 is secured by screws 10. The carriage scale is of the usual construction and extends substantially throughout the length of the platen and is provided with the usual markings and numerical indices; the 75 distance between adjacent marks corresponding to a letter space movement of the carriage. The shift rail 7 carries a pointer 11 which coöperates with the carriage scale 9 in the usual manner. The construction thus 80 far described is the same as that employed in the Remington machine.

The left-hand screw 10 which secures the carriage scale in place also connects a bracket arm 12 to the carriage. This bracket arm 85 extends to the left and is projected downwardly at its outer end as indicated at 13 where a screw 14 connects a bar 15 to the bracket. A downwardly and forwardly projecting bracket arm 16 is secured to the carriage by the screw 10 at the opposite end of the carriage scale and a screw 17 secures the right-hand end of the bar 15 to this bracket. The construction is such that the bar 15 is arranged adjacent to and parallel with the 90 carriage scale, leaving an intervening space 18 between the two through which the pointer 11 may be seen. From an inspection of Fig. 1 it will be seen that the bar 15 extends slightly forward of the pointer 11 and 100 at the left-hand end extends lengthwise beyond the scale 9. An auxiliary scale or centering device 19, which is preferably made of sheet metal, is mounted to slide along the bar 15. This scale may be mounted for adjustment in any one of a variety of ways.

In Figs. 1 and 2 the member 19 is provided with fingers or cleats 20 which are bent around the edges of the bar 15 to connect it to said bar and afford a sliding movement of 5 the auxiliary or centering scale on the bar 15. The front face of the member 19 is provided with a scale, the indices or markings 21 on which are spaced according to the corresponding indices 22 on the carriage scale 9; 10 that is to say, they are a letter-space distance apart. The numeral indices 23 on the member 19 extend progressively from right to left, whereas the numerical indices on the carriage scale extend progressively from left 15 to right. In short the numerical indices on the one scale progress in an opposite direction from those on the other scale. It will be observed that the member 19 is substantially one-half the length of the carriage scale and 20 yet the numerical indices range from "0" to "70" as on the carriage scale. If, for instance, the carriage scale 9 is seven inches long, the sliding scale 19 is preferably three and one-half inches long with numerical indices corresponding to those on the carriage scale. The divisions on the sliding scale therefore have double the value of those on the carriage scale 9 in the present instance, although this, as well as the length of the 25 auxiliary scale, may be varied at will, as will hereinafter more clearly appear, but it is desirable to have the value of the divisions on the sliding scale a multiple of those on the carriage scale 9. From an inspection of 30 Figs. 1 and 2 it will be understood that the pointer 11 not only coöperates with the carriage scale 9 in the usual manner but that it also coöperates with the auxiliary carriage scale 19 for purposes which will hereinafter 35 more clearly appear. A pointer 25 is or may be struck up from the sheet metal of which the sliding scale 19 is made and this pointer may extend from the zero point or from the "1" point on the scale 19. Said pointer 25 40 extends towards and registers with the indices on the carriage scale 9. While I prefer to use the pointer 25, the zero index mark itself may be employed for this purpose and the pointer 25 eliminated.

45 The device is particularly adapted for centering short lines or headings on a page, so that the written matter is arranged as is shown by the following example:—

50 **BRANSON'S SLIDING CENTERING SCALE**
simple in construction
Easy to use.
This is how it does its work.
Saves time.
Conduces to Accuracy.

55 In the use of my device shown in Figs. 1 and 2, the sliding scale 19 is moved until its zero pointer indicates on the scale 9 the space or position at which the operator 60 wishes to center the work, which is at "40"

in the foregoing example, and the scale 19 is allowed to remain in its adjusted position so long as the point selected constitutes the required center. All that is then necessary is to ascertain the number of spaces any particular line will occupy and to commence writing at that number or degree on the auxiliary scale, as indicated by the pointer 11. The sliding scale 19 being numbered to double the space value of the scale 9, the required line of writing will be equally distributed half to the left and half to the right of the indicated center. As an illustration, take the line in the foregoing example which reads "simple in construction". The centering pointer 25 is set at the point "40" on the carriage scale 9. It will be observed that the line in question contains twenty-two letters and spaces. The operator moves the carriage until the index mark indicating 65 the point "22" on the auxiliary scale 19 is in register with the pointer 11 and then proceeds to write the line "simple in construction". The line will be evenly divided with eleven letters and spaces to either side of the 70 selected center "40", the line beginning at "29" and ending at "50" on the scale 9. The rest of the work contained in the foregoing example is centered from the same point and is properly divided in a like manner on 75 each side thereof. It will be observed that the beginning of each line is indicated on the auxiliary scale 19 and the end of the line is indicated on the carriage scale 9.

80 In Fig. 3 I have indicated a modification 100 of the construction in which the carriage scale 9 itself constitutes a carrier for the sliding member 19^a which is arranged above and back of the carriage scale, and has on its face the scale marks or indices corresponding to 105 the scale 19. A centering pointer 25^a is formed on the member 19^a and projects over the face of the carriage scale and registers with the indices thereon.

85 In Fig. 4 essentially the same construction 110 is illustrated except that the centering scale 19^a is arranged below instead of above the carriage scale 9.

90 In Fig. 5 I have shown a construction in which the carriage scale 9^a has a central longitudinally extending slot with corresponding indices on opposite sides of the slot to form a double scale. A central auxiliary scale 19^b is connected to the main scale by shouldered screws 26 which slide in the central slot in the scale 9^a and oppositely disposed pointers 25^b are provided on the auxiliary scale for coöperation with both of the duplicate scales on the upper and lower edges of the main carriage scale member 9^a. 115 120 125

95 The operation of the different modified constructions thus far described is essentially the same as that described in connection with Figs. 1 and 2.

100 It is often desirable in writing headings to 130

provide double or triple spacing; that is to say, a full or double letter space between letters, thus:—

5 B O O K K E E P I N G

10 B O O K K E E P I N G

In order that it may be unnecessary for the operator to make any calculation to take into account the spaces between the letters in centering a line of this character, I have provided in the construction shown in Figs. 6, 10 7 and 8 a special multiplex auxiliary scale for this purpose. In this construction the screws 10 that secure the carriage scale to 15 the arms 8 likewise connect bracket arms 27 to the carriage. The lower ends of these arms form bearings in which a rod 28 is seated and secured at its ends. Surrounding this rod is a tubular member 19^c which is 20 provided with indices on different faces or sides thereof, the numerical indices on one face differing from those on another face so as to provide scales of different values. A 25 disk-like or circular pointer 25^c is secured to the tubular scale 19^c so as to register with the indices on the carriage scale 9, irrespective of the circular adjustment of the tubular scale on its rod 28. The three faces or 30 scales of the member 19^c are represented at *a*, *b* and *c* in Fig. 8 for use in single, double and triple spacing. Thus the scale *a*, for instance, corresponds to the single spacing scales hereinbefore described, whereas the scale *b* for double spacing may have indices 35 from "0" to "35" and be so proportioned that the spaces between each pair of adjacent index marks give it a value which will afford a full letter space between adjacent letters. Thus,

40 B O O K K E E P I N G

On the other hand, it may be desirable to leave two spaces between adjacent letters and the third or triple space scale *c* may have 45 a corresponding value, the scale being from "0" to "24".

In writing the headings in which a full letter space is provided between adjacent letters the multiplex scale 19^c is turned to expose the scale *b* to the operator. The line to be written we shall say, for example, consists of the words—

C E N T E R I N G S C A L E .

55 The words and spaces of this line will be found to occupy twenty-eight letters space points of the carriage scale 9. The operator, however, only counts the number of letters in the line which is fourteen and the spaces 60 between words, giving a single space value to each double space. This will give a line which is calculated as fifteen. The centering or multiplex scale is then adjusted along the rod 28 to attain the proper center in a 65 manner hereinbefore described and the car-

riage is set so as to bring the index mark, designating the point "15" on the scale *b* into register with the pointer 11 when the line may be written and spaced as shown above and the line will be properly centered from the selected point with an equal number of letters or spaces on either side thereof.

70 Various changes may be made in the details of construction and arrangement of parts without departing from my invention.

75 What I claim as new and desire to secure by Letters Patent, is:—

1. In a typewriting machine, the combination of a carriage, two scales for the carriage, index numerals on one scale progressing in an opposite direction from those on the other scale, pointing means, and means for effecting a relative adjustment between said scales.

80 2. In a typewriting machine, the combination of a carriage, two carriage scales, numerical indices bounding a given extent of one scale having a different value from numerical indices bounding a like extent of the other scale, said numerical indices on the two scales progressing in opposite directions, 85 means for effecting a relative adjustment between the two scales, and a pointer coöperating with both of said scales.

90 3. In a typewriting machine, the combination of a carriage, a carriage scale with numerical indices corresponding to the letter space movements of the carriage, a second carriage scale with numerical indices of a different value from those employed to indicate the same extent of the first mentioned 100 scale, a pointer coöperative with both of said scales, and means for effecting a relative adjustment between said scales.

95 4. In a typewriting machine, the combination of a carriage, a carriage scale substantially the length of the platen, a second carriage scale substantially one half the length of the first mentioned scale, a pointer which coöperates with both of said scales, and means for effecting a relative adjustment between said scales.

105 5. In a typewriting machine, the combination of a carriage, a carriage scale substantially the length of the platen, a second carriage scale substantially one-half the length 110 of the first mentioned scale and with the same numerical indices thereon, a pointer which coöperates with both of said scales, and means for effecting a relative adjustment between said scales.

120 6. In a typewriting machine, the combination with a carriage, of a carriage scale substantially the length of the platen, a second carriage scale substantially one - half the length of the platen, the numerical indices on 125 one of said scales progressing in an opposite direction from those on the other scale, a pointer coöperative with said scales, and means for effecting a relative adjustment between said scales.

7. In a typewriting machine, the combination of a carriage, two parallel carriage scales arranged adjacent to each other and mounted for relative longitudinal adjustment, numerical indices on one of said scales progressing in an opposite direction from numerical indices on the other scale, and a pointer coöperative with both of said scales.
8. In a typewriting machine, the combination of a carriage, two parallel carriage scales arranged adjacent to each other and mounted for relative longitudinal adjustment, a pointer on the adjustable scale which coöperates with the indices on the other scale, numerical indices on one of said scales progressing in an opposite direction from numerical indices on the other scale, and a second pointer coöperative with both of said scales.
9. In a typewriting machine, the combination of a carriage, two parallel carriage scales arranged adjacent to each other and mounted for relative longitudinal adjustment, one of said scales being substantially one half the length of the other, a pointer on the adjustable scale which coöperates with the indices on the other scale, the numerical indices on one of said scales progressing in an opposite direction from the numerical indices on the other scale, and a second pointer coöperative with both of said scales.
10. In a typewriting machine, the combination with a carriage, of a carriage scale, an auxiliary multiplex scale mounted for adjustment relatively to said carriage scale both longitudinally thereof and to bring any scale into use, and coöperative indicating means.
11. In a typewriting machine, the combination with a carriage, of a carriage scale, an auxiliary multiplex scale mounted for adjustment longitudinally of said carriage scale and to turn to bring any one of several scales into use, and a pointer coöperative with said scales.
12. In a typewriting machine, the combination with a carriage, of a carriage scale, an auxiliary multiplex scale mounted for adjustment longitudinally of said carriage scale and to turn to bring any one of several scales into use, the auxiliary multiplex scale being substantially one-half the length of the carriage scale and the numerical indices on one scale progressing in an opposite direction from those on the other scale.

Signed at Leicester, England, this 12th day 55
of September, A. D. 1907.

EDWIN F. M. BRANSON.
